UNITED STATES PATENT OFFICE.

EDWARD A. BARNES, OF FORT WAYNE, INDIANA, ASSIGNOR TO GENERAL ELECTRIC COMPANY, A CORPORATION OF NEW YORK.

OIL-FURNACE.

No. 900,695.

Specification of Letters Patent.

Patented Oct. 13, 1908.

Application filed February 19, 1906. Serial No. 301,805.

To all whom it may concern:

Be it known that I, EDWARD A. BARNES, a citizen of the United States, residing at Fort Wayne, county of Allen, State of Indiana, 5 have invented certain new and useful Improvements in Oil-Furnaces, of which the following is a specification.

This invention relates to furnaces for melting metals, in which the metal is contained in 10 a crucible placed in a fire brick or other suitable receptacle or fire chamber into which the products of combustion are directed from a suitable burner or fire-box.

The invention consists in an improved construction of the furnace by means of which a whirling or rotating flame is generated at 15 the bottom of the fire chamber and follows a spiral or helical course around the crucible or pot, and returns over the top of the crucible 20 to the exit flue, whereby a far more even and uniform heating effect is produced, and considerable economy of fuel and time is effected.

In the accompanying drawings, illustrating 25 one of the embodiments of the invention, Figure 1 is a plan view of a furnace; Fig. 2 is a front elevation of the same, partly in section; and Fig. 3 is a cross section of the same.

In Figs. 1 and 2 the furnace is shown as provided with two holes for the pots or crucibles 1, but it is evident that any number of holes may be provided, each one having a chamber 2, preferably circular in horizontal cross section, formed by thick walls 3 of brick or other material, and provided with two or 35 more lids or covers 4. The pot is preferably raised above the floor of the chamber by suitable supports 5, Fig. 3.

Along the front of the furnace runs an air pipe 6 through which air under pressure is 40 supplied to the burner nozzles 7, which extend through the walls of the furnace into the chambers. Adjacent to the main air pipe, in which the pressure is preferably about 6 to 8 ounces to the square inch, is an 45 auxiliary air pipe 8 in which the pressure is preferably about twenty pounds. A third pipe 9 supplies liquid fuel, such as oil, under a pressure, preferably of about thirty pounds. Branch pipes 10 and 11 run from the small 50 air pipe and the oil pipe respectively to a mixing chamber 12, the flow of fluid through each pipe being controlled by a suitable valve 13, whose spindle 14 rises above the floor or grating 15 covering the brick-walled trench 55 16 in which the pipes are laid. The spindle

17 of the valve 18 in the main air pipe also rises above this floor, and all the spindles have suitable handwheels 19 for operating them.

I cause the burner nozzle 7 to enter the chamber 2 on a tangent to one side thereof, as clearly shown in Fig. 1, and in addition to this, I provide the walls of the chamber with a spiral or helical duct or channel 20 which makes preferably about one and a half turns 60 and terminates below the level of the mouth 21 of the flue 22 which leads to the main horizontal flue 23 that runs to the stack (not shown). The nozzle 7 communicates with the lower end of the channel 20. The result 70 of this construction is to cause the stream or column of burning gases from the nozzle to revolve or whirl around the inside the lower portion of the chamber and hug the channel or duct. The whirling flame leaves the 75 channel or duct adjacent the bottom of the pot and wraps itself as closely as possible around it while passing upward in the annular space between the pot and the smooth or unchanneled wall of the chamber, giving an 80 almost perfectly uniform heat. After the top of the crucible has been reached, the flame continues to gyrate around and then laps over the top of the crucible, sweeping 85 downward to the flue 22 and thus tending by its reverberatory action to heat from the top as well as from the bottom. It is found in practice that this construction so directs the flame as to avoid wasteful heating of the refractory lining of the furnace and effectively 90 heats the crucible by generating a whirling flame at the bottom of the fire chamber and concentrating said flame around the entire exposed surface of the crucible, thus effecting a decided economy of time and fuel over 95 furnaces hitherto used. Every heat unit that is expended in heating and rendering incandescent the walls of a furnace of this sort means loss in efficiency, except as to the heat applied at the bottom of the chamber 100 which causes the rising gases to help distribute the rotating flame and to counteract reverberatory action below the level of the exit opening.

In accordance with the provisions of the 105 patent statutes, I have described the principle of operation of my invention, together with the apparatus which I now consider to represent the best embodiment thereof; but I desire to have it understood that the appa- 110

status shown is only illustrative, and that the invention can be carried out by other means.

What I claim as new and desire to secure by Letters Patent of the United States, is:

5. 1. In a melting furnace, the combination of a cylindrical fire chamber, an exit flue leading from the upper portion of the chamber, a helical duct or channel in the inner wall of the lower portion of the chamber 10 which terminates below the opening of the exit flue, the wall above the end of the duct being smooth or unchanneled, and a burner nozzle which discharges into the beginning of the duct to generate a whirling or rotating flame at the bottom of the fire chamber.
10. 2. In a crucible furnace having an exit flue, the combination of a chamber for the crucible which affords free passage for the flame around it and over its top to the exit flue, means which supports the bottom of the crucible above the floor of the chamber, a helical channel or duct in the lower portion 20 of the wall of the chamber which terminates adjacent the bottom of the crucible and delivers the flame in a whirling column about said crucible, and a burner nozzle which discharges into the channel to generate the whirling or rotating column of flame.
25. 3. In a crucible furnace, the combination

of a cylindrical chamber, an exit flue leading 39 from the chamber at a point below its top to bend the flame down over the top of the crucible, a helical channel in the lower portion of the wall of the chamber which terminates below the exit flue, and a burner 35 nozzle which discharges tangentially into the beginning of the channel to generate a whirling flame at the bottom of the chamber.

4. In a crucible furnace, the combination of a cylindrical chamber, a radially extending exit flue in the chamber wall located below its top to bend the flame down over the top of the crucible, a support which holds the bottom of the crucible above the floor of the chamber, a helical channel in the inner wall 45 of the chamber extending from a point adjacent the floor to a point adjacent the top of the support, and a burner nozzle discharging into the lower end of the channel to generate a whirling flame at the bottom of the chamber. 50

In witness whereof, I have hereunto set my hand this fifteenth day of February, 1906.

EDWARD A. BARNES.
